UNITED STATES PATENT OFFICE.

JOHN D. MORGAN, OF SUMMIT, NEW JERSEY, ASSIGNOR TO GOSS PRINTING PRESS COMPANY, OF CHICAGO, ILLINOIS, A CORPORATION OF ILLINOIS.

FOLDING-MACHINE.

1,029,140.

Specification of Letters Patent. Patented June 11, 1912.

Application filed April 5, 1911. Serial No. 619,157.

To all whom it may concern:

Be it known that I, JOHN D. MORGAN, a citizen of the United States, residing at Summit, in the county of Union and State 5 of New Jersey, have invented new and useful Improvements in Folding-Machines, of which the following is a specification.

The invention relates to folding machines and more especially to machines in which 10 printed sheets are associated, and folded to produce a magazine or pamphlet.

Objects of the invention are to provide a novel mechanism which will fold sheets at high speed; to provide for folding and carrying 15 jaws which may operate within the limits of the speed of such mechanism and at the same time serve the machine sufficiently rapidly to enable it to run at the top speed of the press; to provide novel 20 folding jaws and associated mechanism which will simplify the construction of the machine, and to provide such mechanism which will deliver the product in a convenient and suitable manner. These and other 25 objects of invention will in part be obvious and will in part more fully appear herein.

The invention consists in the novel parts, arrangements, constructions, combinations and improvements, herein shown and described.

The accompanying drawings, referred to herein and forming a part hereof, illustrate one embodiment of the invention, the same serving in connection with the description 35 herein to explain the principles of the invention.

Of the drawings: Figure 1 is a side elevation (with the front frame removed for the sake of clearness) of a machine constructed in accordance with the principles of invention; Fig. 2 is an end elevation looking at Fig. 1 from the right; Fig. 3 is a sectional plan on the line A—B of Fig. 1, looking in the direction of the arrows; Fig. 45 4 is a fragmentary plan, on an enlarged scale, of the folding jaw and the folding blade during the infolding of the sheet band; Fig. 5 is an elevation, partly dia-grammatic, showing a different arrangement of the mechanism.

Referring to the accompanying drawings, illustrated by way of example, one embodiment of the invention, suitable means are

shown for feeding in a web x . In the embodied form the web is shown fed in between tapes 3 and 4, running over rollers 1 and 2, suitably mounted in the machine frame. The web x is directed to suitable severing devices for the purpose of severing it into sheets. The severing devices are 55 illustrated as opposed rotary cutters comprising disks 5 and 6 mounted respectively upon shafts 7 and 8 mounted in the machine frame and suitably driven. Each set of disks, respectively, carries one a knife 9 and 60 the other a knife 10, which knives co-operate to cut the web into sheets.

In the present embodiment successive sheet lengths are collected or associated, and for this purpose there is employed in the 70 illustrated machine a three-way collecting cylinder 20 carried upon a shaft 21, journaled upon the machine frame and driven in a suitable manner. The collecting cylinder 20 is provided with sets of grippers 22, 75 23 and 24 for collecting the sheets and releasing them after the proper number of sheets has been collected or associated. Suitable means will be provided for opening and closing these sets of grippers at the 80 proper time to take and release the sheet or sheets.

Means are provided for associating additional sheets with those collected from the web or webs x , and means are shown herein for feeding both a cover and an insert. In the embodied form thereof, tapes 25 and 26 are provided, running over series of rollers 27 and 28 for feeding a sheet to the collecting cylinder 20. This sheet may be 85 taken on the collecting cylinder after the sheet bundle has been stripped therefrom and before the first sheet of the new bundle is taken, the sheet fed in between the tapes 25 and 26 being thus between the collecting 90 cylinder and the bundle of sheets. With the machine folding in the manner illustrated in Fig. 1, this fed-in sheet y would constitute an insert. The end of the web running down between the rotary cutters is guided 95 by sets 30 and 31 of throat or guide bars supported, respectively, upon rods 32 and 33 carried upon the machine frame. Suitable means are provided for insuring the bundle of sheets leaving the cylinder at the 100 right time and in the right position, and 105

for this purpose stripper blades 34 are provided which will move inwardly just in time to pass beneath the front end of a group of sheets which has been completed 5 and is to be progressed forward through the machine to be subjected to the next succeeding operation.

Means are provided for feeding an additional sheet to be associated with a bundle 10 of sheets upon the opposite side thereof from the additional sheet γ previously fed in. For this purpose tapes 35 and 36 are provided, in the present embodiment, running over series of rolls 37 and 38. Suitable 15 gages or front stops, etc., may be provided in connection with each of these sheet feeding devices but are omitted from the drawings for the sake of clearness. In this embodiment this sheet is not fed from the 20 collecting cylinder but into the pathway of the bundle of sheets along which they travel after leaving the collecting cylinder. A series of guide fingers 39 and 40 may be provided to direct the sheet bundle and the 25 extra fed sheet both into the proper path of travel. With the machine arranged for folding in the manner illustrated in Fig. 1, the second additional sheet α would constitute the cover of the magazine or pamphlet. Suitable holding tapes may be provided 30 about the collecting cylinder to hold the sheets in place as required.

In the present embodiment means are provided for stitching or stapling the bundle of 35 sheets and the cover and insert, or any of them, together prior to folding. In the embodied form there are shown two stationary stitchers 41 and 42 mounted respectively upon supporting rods 43 and 44 carried 40 upon the machine frame and actuated in a suitable manner. The clenching dies 45 and 46 are shown on the opposite side of the path of travel of the sheets. A suitable stop or gage is provided for arresting and 45 registering the sheets in position for stitching, and holding them at rest during the stitching operation, the stop being then withdrawn to permit the stitched bundle of sheets to progress forward to the folding position. The stop or gage is shown as a 50 blade 47 mounted upon rods 48 and 49 working in apertured guide lugs 50 and 51 formed on the machine frame. These rods are provided at their other end with cam 55 rolls 52 and 53 in coöperative relation with cams 54 and 55 fixed upon the cam shaft 56 which is suitably journaled at 57 and 58 upon the machine frame. Springs 70 serve to keep cam rolls 52 and 53 to their cams. 60 The shaft 56 is driven by the miter gears 59 from the shaft 60.

Suitable guiding and progressing means 65 for the sheets along their pathway are provided, said means comprising a series of tapes 61 running over rolls 62 and 63, and a

series of guide bars 64 upon one side of the pathway of the sheets, and a series of tapes 65 running over the rollers 37 and over rollers 56, and also guide bars 67 upon the other side of the path of travel of the sheets. 70 These tapes and guide bars are not all of the same length, certain of them reaching only to the folding station, while others run beyond said station, the purpose being to feed the sheets forward with certainty and speed 75 and yet to permit freedom of movement in the folding off.

In the form of folding mechanism provided by the invention the bundle of sheets is folded and carried away by the folding 80 jaws and a longitudinal rotation of the folding jaws relatively to their carrier is imparted, and in the embodied form this rotation is effected while the bundle of folded sheets is being carried by the jaws between 85 the folding-in position and the delivery position, whereby the folded magazine or pamphlet may be delivered to better advantage. According to one feature of the invention the bundle of sheets is fed down 90 a vertical path, is folded into the folding jaws in such vertical position, but is delivered horizontally or flat at the delivery position by reason of such longitudinal rotation of the jaws. 95

In accordance with one feature of the invention, and in the embodied form, a plurality of folding jaws coming successively to one folding-in position or station, and co-operating there with one folding blade and passing thence successively to one delivery position or station are provided. In said embodied form a hollow pedestal 80 is formed on the machine frame bearing within itself a vertical shaft 81. Projecting 100 from said shaft are four arms, or spiders 82. Each of these spiders terminates in a shouldered portion 83 at the shaft 81. A cylindrical sleeve 84 is rotatably mounted upon each arm or spider 82, and is held in 110 position by a pin 85 fixed upon said spider engaging a slot 86 in the sleeve 84 by means of a strong spiral spring 87 fastened at one end to the shoulder 83, as shown at 88, and at the other end to the sleeve 84, as shown 115 at 89. The sleeve 84 terminates in, or has connected thereto, the shaft or axis 90 of the gripper jaws 91 and 92. The jaw 91 is fixed to the shaft 90, the jaw 92 being mounted to swing upon the shaft 90 but being held normally closed by the spring 93. Fixed to the jaw 92 is the trip arm 104 provided with a cam roll or ball 105. 120

Suitable means for opening the jaw 92 against its spring at the folding in position 125 and also at the delivery position are provided. At the folding-in station or position, the cam piece 106 is rotatably mounted upon the machine frame, and is driven by miter gears 107 from the shaft 108, which 130

is suitably connected to the driving shaft of the machine. At the delivery position a stationary cam 109 is provided upon which the roll 105 rides to open the folding 5 jaws.

In the present embodiment the rotatory movement of the folding jaws is intermittent, and to effect this movement, suitable means are provided, the embodied form 10 thereof comprising what may be termed a quadruple Geneva movement. A plate 110 is fixed to the bottom of the shaft 81, and is provided with four radial slots 111, said slots being 90 degrees apart. Between said 15 slots the plate is cut away in the shape of a segment of a circle. Journaled by a stub shaft 112 on the frame of the machine is a continuously rotating plate 113 carrying a circular disk 114 fitting into the circular 20 parts of the plate 110. Fixed on the plate 113 is a pin 115. The disk 114 keeps the plate 110 stationary until the pin 115 engages one of the slots 111 when the plate 25 110, and with it the shaft 81 and the folding jaws carried thereby, receive a quarter rotation. The shaft 112 is driven by the miter gears 116 upon the shaft 117.

In the present embodiment the folding blade is moved forward to tuck the sheet 30 bundle into the opened folding jaws, and the folding blade 120 is shown carried upon rods 121 and 122 mounted and guided, respectively, in apertured lugs 123 and 124 upon the machine frame. The rods 121 and 122 35 are provided, respectively, with cam rolls 125 and 126 which coöperate with corresponding cams 127 and 128 upon the rotating shaft 60. Springs 129 and 130 serve to hold the cam wheels to their cams. The 40 shaft 60 is driven by miter gears 131 upon the shaft 132.

The folding jaws are longitudinally rotated by suitable means, the embodied form 45 thereof comprising an arm 133 fixed to each of the sleeves 84 and carrying a cam roll 134. Stationary upon the machine frame is provided a corresponding arm 135 so shaped and located as to longitudinally rotate the folding jaws about their carrier.

50 The manner of operation of the herein described mechanism will doubtless be understood in detail from the foregoing description, but a brief résumé thereof will now be given.

55 One or more webs α are run down between the rollers 1 and 2, between the disks 5 and 6, and between the guide bars 30 and 31, the end of the web or webs being grasped by one of the sets of grippers on the collecting cylinder 20. If it be assumed that an insert is being fed, a sheet y has been previously run between the tapes 25 and 26 to said grippers. As the end of the web α is 60 grasped by the gripper on the cylinder 20, the rotary cutters 9 and 10 sever the sheet

from the web. The end of the web then runs down between the guides 30 and 31 to be grasped by the next gripper upon the cylinder 20. If the printing cylinders are four plates or sheets around, the cylinder 20 70 will associate four sheets or four groups of sheets (dependent upon the number of webs run) at each set of grippers. When the full number of sheets for the bundle is completed the stripper 34, acting when the grippers are opened, will take the bundle from the cylinder and the bundle will be directed downwardly along the vertical path of travel to the stitchers. At about the same time the cover sheet α is 80 fed into this pathway, and travels down with the bundle of sheets until they are all brought to rest against the stop 47. They here receive accurate, independent register prior to stitching. After the stitching operation is performed, the stop 47 is withdrawn and the stitched bundle of sheets α passes 85 downward to the folding position. One of the pairs of folding jaws 91 and 92 just at this instant comes to rest at the center of 90 the stitched sheet bundle and along the line of the stitches, and the folding blade 120 forces the bundle of sheets in between the open folding jaws. The jaws, which have been held open by the cam 106, now snap 95 together and the pair of jaws with the folded sheets therein move toward the delivery station. In the next quarter turn another set of jaws is at the folding position, or if only two sets of jaws are used the rest will 100 be at the end of the half turn. As the jaws swing around carrying the folded pamphlet α vertically therein, the cam wheel 134 will engage with the cam 135 and the set of jaws will be rotated longitudinally of 105 itself on its carrier until the pamphlet or magazine α is in the horizontal position just over the delivery belt. The cam 109 now acts upon the trip 104 to open the jaws and release the magazine upon the delivery 110 belt. A suitably curved or otherwise shaped table may be provided at the delivery position, and along the approach thereto, if desired, to insure the correct positioning or laying on of the completed magazine or 115 pamphlet upon the delivery tapes or belt. Such table is omitted from the drawing for the sake of clearness in showing the other parts of the mechanism.

The invention, in its broader aspects, is 120 not limited to the particular construction shown, nor to any particular constructions by which it has been or may be carried into effect, as many changes may be made in the construction without departing from the 125 main principles of the invention and without sacrificing its chief advantages.

What I do claim as my invention and desire to secure by Letters Patent, is:

1. A folding machine including in combi- 130

- nation a pair of folding jaws, means for folding a sheet thereinto, and means for longitudinally rotating said jaws to deliver the folded sheet in a position transverse to that in which the sheet was folded into the jaws.
2. A folding machine including in combination a pair of folding jaws traveling between a folding-in and a delivery position, means for folding a sheet into said jaws at the folding-in position, means for longitudinally rotating said jaws as they travel toward the delivery position, and means for causing said jaws to deliver the folded sheet at the delivery position.
3. A folding machine including in combination a pair of folding jaws traveling between a folding-in and a delivery position, means for folding a sheet into the jaws at the folding-in position, and means for rotating said jaws longitudinally to deliver the sheet in a position transverse to that in which the sheet was folded into the jaws.
4. A folding machine including in combination a pair of folding jaws, movable between a vertical and a horizontal position considered longitudinally of the jaws, and means for folding a sheet into the jaws in one of said positions and means for releasing the folded sheet from the jaws in the other of said positions.
5. A folding machine including in combination a pair of intermittently traveling folding jaws traveling between and coming to rest at both a folding position and a delivery position, said folding jaws being longitudinally rotatable, means for feeding a sheet along a vertical path to said jaws, means for folding the sheet into the jaws while they are at rest at the feeding position, means for rotating the pair of jaws into a horizontal position as they travel toward the delivery position, means for causing the jaws to release the sheet at the delivery position, and a horizontal conveyer for receiving and conveying away the sheets from said folding jaws.
6. A folding machine including in combination a pair of folding jaws rotatable longitudinally between a vertical and horizontal position, means for feeding a sheet along a vertical path to said jaws, means for folding the sheet into said jaws, and means for rotating said jaws into a horizontal position to deliver the sheet.
7. A folding machine including in combination a pair of folding jaws rotatable longitudinally between a vertical and horizontal position, means for feeding a sheet along a vertical path to said jaws, means for folding the sheet into said jaws, means for rotating said jaws into a horizontal position to deliver the sheet, and a horizontal conveyer for receiving and conveying away the sheets from said folding jaws.
8. A folding machine including in combination a traveling carrier, a plurality of pairs of folding jaws mounted on said carrier, a folding station and a delivery station, means for intermittently moving said carrier to progress the pairs of folding jaws between said folding station and delivery station and to present simultaneously one pair of folding jaws at rest at the folding station and another pair of folding jaws at rest at the delivery station, a folding blade cooperating with the folding jaws at the folding station, and means for causing the folding jaws to release the folded sheets at the delivery station.
9. A folding machine including in combination a traveling carrier, a plurality of pairs of folding jaws mounted on said carrier, a folding station and a delivery station, and means for longitudinally rotating a pair of jaws whereby the folded sheet may be delivered in a position transverse to that in which it was folded into said jaws.
10. A folding machine including in combination a traveling carrier, a plurality of pairs of folding jaws mounted on said carrier, a folding station and a delivery station, one pair of folding jaws being presented at the folding position when another pair of folding jaws is at the delivery position, and means for rotating a pair of jaws longitudinally to deliver the sheet in a position transverse to that in which it is folded in.
11. A folding machine including in combination a traveling carrier, a plurality of pairs of folding jaws mounted on said carrier, a folding station and a delivery station, one pair of folding jaws being presented at the folding position when another pair of folding jaws is at the delivery position, and means for rotating a pair of jaws longitudinally while traveling from the folding to the delivery position.
12. A folding machine including in combination means for delivering a bundle of sheets into a straight vertical pathway, means for directing said sheets along said straight vertical pathway, a mechanism located intermediately along said vertical pathway for operating upon the sheets, folding means located farther down said pathway than said first mentioned mechanism, means for arresting the sheets in position to be operated upon by said mechanism and for releasing them to permit them to proceed along said pathway to said folding means to be folded thereby.
13. A folding machine including in combination, means for delivering a bundle of sheets into a straight vertical pathway, means for directing said sheets along said straight vertical pathway, stitching mechanism located intermediately along said pathway, folding means along said pathway below said stitching mechanism, and means for arresting said sheets in position to be folded thereby.

tion to be stitched by said mechanism and for permitting the sheets to proceed along said pathway to the folding position after they have been stitched.

5 14. A folding machine including in combination means for feeding sheets downwardly along a vertical pathway, means for arresting said sheets in said pathway, means for stitching said sheets while so arrested, 70 means for folding said sheets in said pathway, and means for delivering the folded sheets horizontally from said pathway.

10 15. A folding machine including in combination means for feeding sheets along a vertical pathway, means for folding said sheets longitudinally of said pathway, and means for delivering the folded sheets horizontally. 75

15 16. A folding machine including in combination a pair of folding jaws mounted upon an axis to open and close, and a support for said axis upon which it is longitudinally rotatable, and means for delivering the folded sheets horizontally. 80

20 17. A folding machine including in combination a pair of folding jaws mounted upon an axis to open and close, a support for said axis upon which it is longitudinally rotatable, and devices for opening said folding jaws in a plurality of positions to which 85

25 30 they are so rotated. 90

25 18. A folding machine including in combination a pair of folding jaws mounted upon an axis to open and close, a support for said axis upon which it is longitudinally rotatable, a folding blade coöperating with 95

30 said pair of jaws to fold a sheet thereinto, and a delivery device for receiving the folded sheet from said pair of jaws after they have been so rotated about their axis. 100

35 40 19. A folding machine including in combination a pair of folding jaws mounted upon an axis, to open and close, a support for said axis upon which it is longitudinally rotatable, and means for intermittently moving said support. 105

45 20. A folding machine including in combination a pair of folding jaws mounted upon an axis to open and close, a support for said axis upon which it is longitudinally rotatable, means for intermittently moving said support, means for opening and closing said 110

50 pair of folding jaws, and a moving folding blade for folding a sheet into said jaws while they are open and at rest. 115

55 21. A folding machine including in combination a pair of folding jaws mounted upon an axis to open and close, a support for said axis upon which it is longitudinally rotatable, and a folding blade movable to 120

60 fold a sheet into said pair of jaws. 125

22. A folding machine including in combination a pair of folding jaws mounted upon an axis to open and close, a support for 130

65 said axis upon which it is longitudinally rotatable, means for opening and closing said

pair of jaws and a folding blade movable to fold a sheet into said jaws while they are open.

23. A folding machine including in combination a pair of folding jaws mounted upon an axis to open and close, a support for said axis upon which it is longitudinally rotatable, and a folding blade coöperating with said jaws to fold a sheet thereinto. 70

24. A folding machine including in combination a plurality of pairs of folding jaws, each pair mounted upon an axis to open and close, a support upon which each pair of jaws is rotatable longitudinally of said axis, and means for folding a sheet into a pair of 80

25 29. A folding machine including in combination a plurality of pairs of folding jaws, each pair mounted upon an axis to open and close, a support upon which each pair of jaws is rotatable longitudinally of said axis independently of any other pair of said folding jaws, and means for folding a sheet 85

30 into a pair of folding jaws. 90

35 39. A folding machine including in combination a plurality of pairs of folding jaws, each pair mounted upon an axis to open and close, a support upon which each pair of jaws is rotatable longitudinally of said axis independently of any other pair of said 95

40 folding jaws, means for folding a sheet into a pair of folding jaws, means for intermittently moving said support between a folding 100

45 and delivery station, and means for rotating a pair of jaws while moving from the folding to the delivery station. 105

50 49. A folding machine including in combination a plurality of pairs of folding jaws, each pair mounted upon an axis to open and close, a support upon which each pair of jaws is rotatable longitudinally of said axis, means for folding a sheet into a pair of 110

55 jaws in a vertical position longitudinally of the jaws, means for rotating said pair of jaws longitudinally with the folded sheet 115

60 therein into a horizontal position, and means for delivering the folded sheet from said jaws in the horizontal position. 120

65 50. A folding machine including in combination a pair of folding jaws openable and closable upon an axis, a rotatable member, an arm and a sleeve one connected to said rotatable member and the other to said pair of jaws, and a spring connecting said arm and sleeve. 125

55 51. A folding machine including in combination a pair of folding jaws openable and closable upon an axis, a rotatable member, an arm and a sleeve one connected to said rotatable member and the other to said pair 130

60 of jaws centrally of their length, and a spring connecting said arm and sleeve. 135

65 52. A folding machine including in combination a pair of folding jaws openable and closable upon an axis, a rotatable member, 140

an arm and a sleeve one connected to said rotatable member and the other to the axis of said pair of jaws, and a spring connecting said arm and sleeve.

5 31. A folding machine including in combination a pair of folding jaws openable and closable upon an axis, a rotatable member, an arm and a sleeve one connected to said rotatable member and the other to the axis 10 of said pair of jaws centrally of the length thereof, and a spring connecting said arm and sleeve.

32. A folding machine including in combination a pair of folding jaws openable and 15 closable upon an axis, a rotatable member, an arm and a sleeve one connected to said rotatable member and the other to said pair of jaws, a spring connecting said arm and sleeve, and means for rotating said arm and 20 sleeve relatively to each other against the action of said spring.

33. A folding machine including in combination a pair of folding jaws openable and closable upon an axis, a rotatable member, 25 an arm and a sleeve one connected to said rotatable member and the other to said pair of jaws, a spring connecting said arm and sleeve, and means for rotating said arm and sleeve relatively to each other against the 30 action of said spring by reason of the rotation of said rotatable member.

34. A folding machine including in combination a pair of folding jaws openable and closable upon an axis, a rotatable member, 35 an arm and a sleeve one connected to said rotatable member and the other to said pair of jaws, a spring connecting said arm and sleeve, means for rotating said arm and sleeve relatively to each other against the 40 action of said spring, and devices for causing said jaws to open and close in a plurality of positions.

35. A folding machine including in combination, means for delivering a bundle of 45 sheets into a straight vertical pathway, means for directing said bundle of flat sheets along said straight vertical pathway, a stationary stitching mechanism located intermediately along said pathway for flat stitching the sheet bundle, a folding mechanism along said pathway below said stitching mechanism, and means for arresting said sheets in registered position to be stitched by said stitching mechanism and for then 50 permitting said sheets to proceed along said pathway to said folding position.

36. A folding machine including in combination, means for delivering a bundle of sheets into a straight vertical pathway,

means for directing said bundle of flat sheets along said straight vertical pathway, a stationary stitching mechanism located intermediately along said pathway for flat stitching the sheet bundle, a folding mechanism along said pathway below said stitching mechanism, and means for arresting said sheets in registered position to be stitched by said stitching mechanism and for then permitting said sheets to proceed along said pathway to said folding position, said folding mechanism being located and adapted to fold the stitched sheets at the stitches.

37. A folding machine including in combination, means for delivering a bundle of sheets into a straight vertical pathway, means for directing said bundle of flat sheets along said straight vertical pathway, a stationary stitching mechanism located intermediately along said pathway for flat stitching the sheet bundle, a folding mechanism along said pathway below said stitching mechanism, and means for arresting said sheets in registered position to be stitched by said stitching mechanism and for then permitting said sheets to proceed along said pathway to said folding position, said folding mechanism being located and adapted to fold the stitched sheets at the stitches, and to deliver the folded sheets without engaging them except at said fold.

38. A folding machine including in combination, means for delivering a bundle of sheets into a straight vertical pathway, means for directing said bundle of flat sheets along said straight vertical pathway, a stationary stitching mechanism located intermediately along said pathway for flat stitching the sheet bundle, a folding mechanism along said pathway below said stitching mechanism, and means for arresting said sheets in registered position to be stitched by said stitching mechanism and for then permitting said sheets to proceed along said pathway to said folding position, said folding mechanism being located and adapted to fold the stitched sheets at the stitches, while in vertical position and means for rotating said folding means while carrying said folded sheets whereby the sheets are delivered horizontally.

In testimony whereof, I have signed my name to this specification, in the presence of two subscribing witnesses.

JOHN D. MORGAN.
